UNITED STATES PATENT OFFICE

166,907

STEREOSCOPIC VIEWER

Harry J. Collins, Milwaukee, Wis., assignor to
David White Company, Milwaukee, Wis., a corporation of Wisconsin

Application August 20, 1951, Serial No. 16,389

Term of patent 14 years

(Cl. D61—1)

To all whom it may concern:

Be it known that I, Harry J. Collins, a citizen of the United States, residing at Milwaukee, in the State of Wisconsin, have invented a new, original, and ornamental Design for Stereoscopic Viewer, of which the following is a specification, reference being had to the accompanying drawing, forming a part hereof.

Fig. 1 is a perspective view of a stereoscopic viewer, showing my new design;

Fig. 2 is a top plan view of the same;

Fig. 3 is a front elevational view; and

Fig. 4 is a side elevational view thereof.

I claim:

The ornamental design for a stereoscopic viewer, as shown.

HARRY J. COLLINS.
